UNITED STATES PATENT OFFICE.

POWHATAN J. WOOLDRIDGE, OF PEWEE VALLEY, KENTUCKY.

SAFETY APPARATUS FOR ELEVATORS.

Application filed December 4, 1918, Serial No. 265,194. Renewed April 8, 1922. Serial No. 550,799.

To all whom it may concern:

Be it known that I, POWHATAN J. WOOLDRIDGE, a citizen of the United States, residing in Pewee Valley, Oldham County, Kentucky, have invented certain new and useful Improvements in Safety Apparatus for Elevators, fully described and represented in the following specification and the accompanying drawings, forming a part 10 of the same.

My invention relates to safety apparatus for elevators and more particularly to an apparatus for preventing open doors at elevator landings when the elevator is not 15 properly opposite the landing.

The main object of the invention is to provide an improved apparatus for preventing an elevator from moving materially away from the landing when the door there- 20 at is open, and for locking the door closed when the elevator is moved away from the landing. Further and more specific ob- 25 jects, features and advantages will more clearly appear from the detail description given below taken in connection with the accompanying drawings which form a part of this specification. In the drawings:—

Fig. 1 is an elevation partly broken away and partly diagrammatic, of an elevator em- 30 bodying part of my improvements in a pre- fered form thereof;

Fig. 2 is a partial section through the ele- 35 vator well at the top of the elevator door at a landing and showing part of the ele- vator in plan view with part of my im- proved apparatus in section taken on the line 2—2 of Fig. 1;

Fig. 3 is a detail vertical view of part of 40 my improved apparatus adapted to be at- tached to the top of the elevator, parts there- 45 of being shown in section to more clearly illustrate the operation thereof; and

Fig. 4 is a section taken on the line 4—4 of Fig. 3.

Referring to the drawings, 5 represents an 45 elevator adapted to be raised and lowered in an elevator well by any well-known or suitable apparatus, preferably by electric power. The top of the elevator is shown at 50 6 and within the elevator is conveniently situated any suitable or well-known control- 55 ling apparatus 7, provided with a handle 8 for affecting in any suitable or well-known manner an electric control circuit, part of 55 which is indicated by the conductors 9. 10

represents an elevator door at one of the landings in the elevator well, which door is adapted to slide back and forth to open and close the door.

Secured to the top of the elevator 6, are 60 a pair of oppositely curved cams 11 and 12, the upper cam 11 being carried by a standard 13 and depending therefrom, and the lower cam 12 extending upwardly from the front side of the elevator. 15 and 16 are 65 two parallel horizontal members connected together at one end by a connecting piece 18 and at the other end provided with right angled turned ends 19 and 20 respectively. The ends 19 and 20 are adapted to have a 70 free sliding movement in guide-ways 21 and 22 supported above the top of the elevator and behind the cams 11 and 12 by a frame 14. The frame 14 is also provided with upper and lower brackets 23 and 24 in which 75 are slidably mounted vertical rods 25 and 26 respectively. The rod 25 is provided with a head 27 bearing against the upper face of member 15, and with a collar 28 fast thereon and normally bearing against 80 a bearing collar 29 of bracket 23 under the action of a spring 30, one end of which bears against the collar 28 and the other end of which bears against the upper part of 85 bracket 23. If desired a nut 31 may be se- cured to the upper end of the rod 25. In a similar manner the rod 26 normally bears against the under face of the member 16 un- 90 der the action of a spring 33, one end of which bears against a collar 34 fast on the rod 26 and the other end against the lower part of the bracket 24. If desired a nut 36 may be secured to the lower end of the rod 26.

It will thus be apparent that the hori- 95 zontal members 15 and 16 may be given a slight upward and downward movement relatively to the elevator from the position shown in Fig. 3 against the resistance of the rod 25 or 26 as the case may be. The springs 30 and 33, however, acting on the rods 25 and 26 normally hold the members 15 and 16 resiliently in the position shown in Fig. 3. When the horizontal members 15 and 16 are moved upwardly or downwardly 105 the parts 19 and 20, operating in the guide-ways 21 and 22, serve as guides for such movements.

Carried on the member 18, but suitably insulated therefrom, is an electric contact bar 37 which normally has contacting therewith 110

two spring contacts 38 and 39 carried upon a bracket 40. The spring contacts 38 and 39 are insulated from one another and from the bracket 40 but are electrically connected 5 to the conductors 9 by means of binding posts 41 and 42 respectively, so that the parts 37, 38 and 39 form a control switch for opening and closing the control circuit 9 upon the horizontal members 15 and 16 being 10 moved upwardly or downwardly. When these horizontal members are so moved, the conducting bar 37 is moved away from the spring contacts 38 and 39, thus opening the control circuit.

15 Pivoted to a stationary part of the elevator well at 43 is a member 44 provided with a slot 45 adapted to be entered by roller 46, pivotally mounted on top of the door 6. When the door 6 is opened by movement 20 thereof in the direction of the arrow 47, as shown in Fig. 4, the roller 46 engages the arms 48 of the member 44 and operating in the slot 45 causes the member 44 to be swung counter clockwise as viewed in Fig. 4 and in 25 between the horizontal members 15 and 16 on top of the elevator. This is, of course, assuming that the elevator is opposite a floor landing in which position the members 15 and 16 are situated to receive the member 44.

30 The opening of the door swings the member 44 as stated, and inserts it into the path of the elevator and the members 15 and 16 to the position indicated in dotted lines 61 in Fig. 4 and in full lines in section in Fig. 3.

35 Thereupon if it be attempted to move the elevator up, the relatively stationary member 44 carried by the elevator well will engage the member 16 preventing it from moving upwardly with the elevator, and causing 40 the contacts 38 and 39, carried upwardly by the elevator, to be separated from the contact bar 37 thus opening the control circuit and causing the elevator to stop, the brakes being applied by any well-known or suitable arrangement as is customary when such 45 a control circuit of the elevator is broken. If it be attempted to move the elevator down when the door is open as above stated, the member 44 will engage the member 15 and 50 prevent it from moving downwardly with the elevator and so cause the contacts 38 and 39 to be moved off the contact bar 37 and open the circuit to stop the elevator and apply the brakes as before. The member 44 is 55 provided with an upturned flange 49 to engage the member 15 and protect parts hereinafter described carried by the member 44. When the door is closed the roller 46 will 60 engage the other arm of the member 44 as the door approaches its closed position and will swing it out of the space between the members 15 and 16, and out of the path of the elevator and all parts connected therewith, and over the top of the door 10 as 65 shown in full lines in Figs. 2 and 4, thus per-

mitting the elevator to be freely moved upwardly or downwardly to other landings.

Pivoted on the end of the member 44 at 50 is a hook 51. A spring 52 normally maintains the hook 51 in the position shown in Fig. 4 in full lines, against a pin 53 secured to the member 44, and in such a position that the hook 51 is adapted on movement of the member 44 to be engaged by a co-operating hook 54 rigidly secured in the elevator well 70 or door frame. Pivoted to the hook 51 at 55 is a lever 56 normally held in the position shown in full lines in Fig. 4 by a spring 57 which pulls the short arm thereof against the body portion of the hook 51 which acts 80 as a stop therefor. When the elevator is opposite the door 10 the long arm of the lever 56 is adapted to be engaged by the projecting part of an upright member 58 which extends upward from the top of the elevator.

When the elevator is materially away from the landing so that the lever 56 is not opposite the outwardly bent abutment part of the upright member 58, then if it be attempted to open the door the roller 46 will tend to swing the member 44 inwardly, but the hook 51 will engage the catch 54 and thus prevent the member 44 being swung inwardly into the path of the elevator, and the arm 48 which is in engagement with the roller 46 will prevent the door from being opened so that the hooks 51 and 54 serve as latches or catches for locking the door 10 in closed position when the elevator is not properly positioned opposite the elevator landing. When, however, the elevator is properly positioned opposite the elevator landing, then as the door 10 is opened and the roller 46 engages the arm 48 and swings 100 the member 44 inwardly about the pivot 43, during the first part of the movement of the member 44 to the position indicated by dotted lines 60 in Fig. 4, the lever 56 engages the abutment member 58 and causes the lever 56 to swing the hook 51 to the left and as shown by dotted lines 63 in Fig. 4 so that the hook 51 will pass clear of the hook 54 when the member 44 is further swung into the path of the elevator. As the door is 110 further opened the roller 46 causes the arm 44 to swing in between the members 15 and 16, the lever 56, by engagement with the member 58, causing the hook 51 to be swung further in a clockwise direction as viewed 120 in Fig. 4 until the lever 56 swings by the member 58 thus permitting the arm 44 to swing freely into the position shown in Fig. 3 and by dotted lines 61 in Fig. 4. When the door is closed and the member 44 returned to its normal position, the lever 56 swings on its pivot 55 in order to pass the member 58, but when it has passed the member 58 the spring 57 returns the lever 56 to its normal position shown in full lines in Fig. 4, 130

and the hook 51 is in a position to cooperate with the hook 54 to lock the door 10 in closed position.

In case it should happen that the door 5 should not be quite closed and the member 44 not swung entirely out of the path of the elevator, but to a point opposite and between the cams 11 and 12, and free of the members 15 and 16, where an up or 10 down movement of the elevator would not cause the opening of the control circuit by action of the switch 37, 38 and 39, then the upward movement of the elevator would cause the cam 11 to engage the member 44 15 and swing it out of the path of the elevator and over the top of the door to its normal position as shown in full lines in Fig. 4. Similarly the downward movement of the elevator would cause the cam 12 to 20 engage the member 44 and similarly force it out of the path of the elevator. Either of these movements will also cause the member 44 to act on the roller 46 to complete the closing of the door and bring the hook 25 51 into operative position with the hook 54 to lock the door in a closed position.

It will be seen from the above that the arrangement not only effectively and efficiently prevents the elevator from being moved materially away from the landing while the elevator door is open, but also securely locks the door closed when the elevator is not properly opposite the landing. It will be understood, of course, that at each landing 30 35 there will be provided a member 44 with its associated parts, so that the doors at all the landings of the elevator well will be properly locked when the elevator is not properly opposite the same, and also upon 40 opening the door at any landing the corresponding member 44 will be inserted into the path of the elevator as shown in Fig. 3 so as to prevent the elevator from moving materially away from the landing. The 45 top of the elevator is preferably cut away as at 64 to provide a recess for accomodating the downward movement of the rod 26. It is also cut away so as to provide a recess for accomodating the downward movement 50 of the member 20 with respect to the top of the elevator.

While I have described a preferred embodiment of my invention and in great detail, I do not desire to be limited to such 55 construction and details since many changes and modifications may be made and the invention embodied in widely differing forms without departing from the spirit and scope of the invention in its broader aspects.

60 It will be noticed that the arrangement and operation of the parts of the apparatus is such that there is no part attached to the elevator well or well door which in its normal position need project, or in the 65 particular construction shown does project,

toward the interior of the well beyond the wall or framework of the well as it exists before the apparatus is added thereto, the swinging arm or member 44 projecting into the path of the elevator only when the elevator is positioned and the well door opened; also that no part of the apparatus carried by the elevator need project beyond the sides or extreme limits of the elevator as it existed before the apparatus 70 75 was applied thereto.

What is claimed is:

1. The combination with an elevator well provided with a floor landing, a landing door, and an elevator operating in said well, and controlling mechanism for said elevator, of stopping mechanism carried by the elevator and independent of said controlling mechanism, and means adapted to be projected into the path of said stopping 80 mechanism by the opening of said door and acting to operate said mechanism to stop the elevator responsive to a movement of the elevator away from the landing. 85

2. The combination with an elevator well provided with a floor landing and a landing door, and an elevator operating in said well, of means preventing the opening of said door except when the elevator is opposite said landing, controlling mechanism 95 carried by the elevator, stopping means carried by the elevator and independent of said controlling mechanism, and means adapted to be projected into the path of said stopping mechanism upon the opening 100 of said door and acting to operate said mechanism to stop the elevator responsive to a movement of the elevator away from the landing. 105

3. The combination with an elevator well provided with a floor landing and a landing door, and an elevator operating in said well, of operating means for the elevator including an electric controlling circuit, mechanism carried by the elevator for 110 opening and closing said circuit, and means adapted to be projected into the path of said mechanism, and actuated by the opening of said door and acting to operate said mechanism to affect said circuit and stop 115 the elevator, responsive to a movement of the elevator away from said floor.

4. The combination of an elevator well provided with a floor landing and a landing door, and an elevator operating in said well, of means preventing the opening of said door except when the elevator is opposite said landing, operating means for the elevator including an electric controlling circuit, mechanism carried by the elevator for 120 opening and closing said circuit, and means adapted to be projected into the path of said mechanism, by the opening of said door and acting to operate said mechanism to affect said circuit and stop the elevator, 125 130

responsive to a movement of the elevator away from said floor in either direction.

5. The combination with an elevator well provided with a floor landing and a landing door, and an elevator operating in said well, of a control switch carried by the elevator, and means adapted to be moved into operative relation to said switch by the opening of said door, said switch being operated thereby to stop the elevator by a movement of the elevator away from the floor when said means is in operative relation to said switch.

6. The combination with an elevator well provided with a floor landing and a landing door, and an elevator operating in said well, of means for locking said door, releasing means on said locking means, and a member carried by said elevator and adapted to contact with and operate said releasing means when the elevator is opposite said landing and said releasing means are actuated by movement of the door, said first mentioned means including a member adapted to be projected into the path of the elevator by the opening of said door and acting to prevent the elevator from moving materially away from said landing when said door is open.

7. The combination with an elevator well provided with a floor landing and a landing door, and an elevator operating in said well, of a member pivoted to the well and adapted to be swung by the opening of said door into the path of the elevator to prevent the elevator moving materially away from said landing when said door is open, means carried by said member for locking said door, and means carried by the elevator for unlocking said locking means when the elevator is opposite said landing.

8. The combination with an elevator well provided with a floor landing and a landing door, and an elevator operating in said well, of controlling mechanism carried by the elevator, stopping mechanism carried by the elevator and independent of said controlling mechanism, a member adapted to be projected into the path of said stopping mechanism without contact therewith by the first part of the opening movement of the door and to be retracted by the last part of the closing movement of the door and operative when projected to prevent the elevator from moving materially away from said landing by coming in contact with said stopping mechanism, means for preventing opening of said door, and means carried by the elevator for releasing the door when the elevator is opposite said landing.

9. The combination with an elevator well provided with a floor landing and a landing door, and an elevator operating in said well, of controlling mechanism carried by the elevator, a member adapted to be pro-

jected into the path of said controlling mechanism by the first part of the opening movement of the door and to be retracted by the last part of the closing movement of the door and operative when projected to 70 cooperate with said controlling mechanism to prevent the elevator from moving materially away from said landing, means for holding said member in its retracted position, said member when held in its retracted position serving to prevent the opening of said door, and means carried by the elevator and serving to permit said member to be projected and the door to be opened when the elevator is opposite said landing. 80

10. The combination with an elevator well provided with a floor landing and a landing door, and an elevator operating in said well, of a member adapted to be projected into the path of the elevator by the opening 85 of said door for preventing the elevator from moving materially away from said landing, said member being adapted to be withdrawn from the path of the elevator by the closing of the door, and means carried by the elevator for completing the withdrawal of said member from the path of the elevator should the door be not sufficiently closed therefor.

11. The combination of an elevator well 95 provided with a floor landing and a landing door, and an elevator operating in said well, of a member adapted to be projected into the path of the elevator by the opening of said door for preventing the elevator from moving materially away from said landing, said member being adapted to be withdrawn from the path of the elevator by the closing of the door, and means whereby movement of the elevator will complete 100 the withdrawal of said member from the path of the elevator and the closing of said door should the door not be otherwise completely closed.

12. The combination of an elevator well 110 provided with a floor landing and a landing door, and an elevator operating in said well, of a stopping member carried by the elevator and resiliently held in normal position with respect to the elevator, means whereby a movement of said stopping member with respect to the elevator will stop the movement of the elevator, and a member carried by the well and adapted to be projected into the path of said stopping member by the 115 opening of said door and adapted to move said stopping member upon movement of the elevator away from the floor landing.

13. The combination of an elevator well 125 provided with a floor landing and a landing door, and an elevator operating in said well, of two horizontal members carried by the elevator, means whereby said members are resiliently held in normal position with respect to the elevator, means whereby a move- 130

ment of either member with respect to the elevator will stop the movement of the elevator, and a member carried by the well and adapted to be projected into the path of 5 and between said horizontal members by the opening of said door.

14. The combination of an elevator well provided with a floor landing and a landing door, and an elevator operating in said well, 10 of a member carried by the elevator and resiliently held in normal position with respect to the elevator, means whereby a movement of said member in either direction with respect to the elevator will stop the movement of the elevator, and a member carried 15 by the well and adapted to be projected upon the opening of said door into position to cause movement of the first said member upon movement of the elevator and to be 20 withdrawn upon the closing of said door.

15. The combination of an elevator well provided with a floor landing and a landing door, and an elevator operating in said well, 25 of a member carried by the elevator and resiliently held in normal position with respect to the elevator, means whereby a movement of said member in either direction with respect to the elevator will stop the movement of the elevator, and a member carried 30 by the well and adapted to be projected upon the opening of said door into position to cause movement of the first said member upon movement of the elevator and to be 35 withdrawn upon the closing of said door, and cams carried by the elevator for completing the withdrawal of the second said member and the closing of the door should the door not be completely closed.

16. The combination of an elevator well 40 provided with a floor landing and a landing door, and an elevator operating in said well, of a member carried by the elevator and resiliently held in normal position with re-

spect to the elevator, an electric control circuit for the elevator, a switch in said circuit 45 carried by the elevator and adapted to be operated by movement of said member in either direction to stop the movement of the elevator, and a member carried by the well and adapted to be projected into the path of 50 the first said member upon the opening of said door and adapted to move the first said member upon movement of the elevator away from the landing.

17. In elevator mechanism, the combination with a well, a door therein, a car, and controlling mechanism on the car including an electric circuit, of a circuit breaker in said circuit, an operating device therefor on the car, and a member located in the well 60 near the door and actuated by opening movement of the door to move into active relation to said circuit breaker operating device, so that upon moderate movement of the car the circuit breaker is operated by 65 cooperation of said member with said operating device.

18. In elevator mechanism, the combination of a well, a door therein, means located on the well for locking the door but permitting slight movement thereof, releasing means for said locking means, and a member carried by the car and acting when the car is close to a predetermined position in the well to contact with and operate said releasing means when said releasing means are actuated by a movement of the door approximately to the point normally permitted by said locking means.

In testimony whereof I have hereunto set 80 my hand in the presence of two subscribing witnesses.

POWHATAN J. WOOLDRIDGE.
